UNITED STATES PATENT OFFICE.

JOSEPH CARTER, OF SASKATOON, SASKATCHEWAN, CANADA.

GAME.

1,398,837.

Specification of Letters Patent. Patented Nov. 29, 1921.

Application filed March 17, 1921. Serial No. 453,094.

To all whom it may concern:

Be it known that I, JOSEPH CARTER, a subject of the King of England, residing at Saskatoon, in the Province of Saskatchewan and Dominion of Canada, have invented new and useful Improvements in Games, of which the following is a specification.

This invention has reference to games, more particularly of the parlor type, although not necessarily confined to such particular type of games, and its object is to provide a simple form of game to be played by one or more persons, wherein skill may take a prominent part in enabling the player 15 to win the game.

The invention comprises a board or table with supports or legs for elevating it above a surface and the board is provided with ends and sides so that light blocks or "men" 20 may be employed and an impeller or mallet may be used acting on the "men" by the impact of blows transmitted from the impeller through the bottom of the table, which may be made more or less elastic for the purpose.

25 At what may be termed the head of the table, there is provided a pocket to catch the men or playing objects as they are impelled through the air by blows struck on the bottom of the table from beneath.

30 The invention will be best understood from a consideration of the following detailed description taken in connection with the accompanying drawing, forming part of this specification, with the understanding, 35 however, that the invention is not confined to any strict conformity with the showing of the drawing but may be changed and modified so long as such changes and modifications mark no material departure from the 40 salient features of the invention as expressed in the appended claims.

In the drawing:

Figure 1 is a perspective view of a game-board embodying the invention.

45 Fig. 2 is a longitudinal vertical section of the structure of Fig. 1, and indicating in dotted lines the manner of playing the game.

Referring to the drawing, there is shown a game-board comprising a bottom member 1, a head member 2, a tail member 3, and side members 4, joined together in any appropriate manner and provided with legs 5 at the corners, so as to support the board upon a table 6 or the like with the under 55 surface of the bottom 1 sufficiently elevated

above the table 6 for the purposes of the invention.

The game-board may, in most part, be made of sufficiently stout cardboard or of veneer or the like, cost and strength of the 60 structure being taken into consideration.

The head 2 is made higher than the other parts of the structure, to carry a pocket 7, and the tail 3 and sides 4 need only be made high enough to prevent the discharge of the 65 playing elements thereover.

Suitable "men" or playing elements 8 are provided and these may be conveniently made of cubical blocks of wood of appropriate size or of some other material than wood, providing an appropriate bulk and weight to possess sufficient inertia to cause these blocks of wood or the like to travel for a sufficient distance through the air, so that when starting from a state of rest from within the 75 structure at a point near the tail board 3, they will reach at least as far as the pocket 7 and drop thereinto.

On the upper face of the bottom member 1, place areas 9 are produced near the tail 80 board 3 and on the same surface of the bottom member are circumscribed areas 10 serving as traps. The blocks 8 are differentiated by coloring or otherwise so that these blocks may be individual to the players. 85 A block 8 is placed upon one of the areas 9 and the mallet 11 is grasped by the hand of the player and a blow is imparted to the under surface of the bottom member 1 close to the area 9 but at a point somewhat to the rear of said area, so that the force of the blow is transmitted to the block in a manner to cause the block to rise in the air toward the pocket 7 and with such force that the block will traverse a path 90 which, if the aim be correct, will cause the block to drop into the pocket 7.

By pre-arrangement among the players, a successful shot, whereby the impelled block 8 will find its way into the pocket 7, 100 will count a certain amount. If the aim of the player be faulty, the block may drop beyond the sides or ends of the board 1 or may drop in a ring 10 or at some other point which will count against the player, 105 either by exacting a forfeit or otherwise. Each player may be allowed a certain number of shots and certain play may demand forfeits or the losing of turns, or any other arrangement to be agreed upon. 110

The game-board provides a means for amusement of two or more people for contest purposes and even one person may find amusement in the endeavor to acquire skill 5 in the projection of the blocks into the pockets 7. The game-board is susceptible of manufacture in the knocked down condition to be assembled and secured together by nails or brads 12 driven through the ends 10 and sides 2, 3 and 4.

The structure is capable of manufacture from cheap material having ample strength for the purpose and hence is adapted to produce game-boards capable of being sold 15 at a small price, with the replacement cost so low that in the event of the game-board being broken, a new game-board may be purchased at an almost negligible cost.

What is claimed is:—

20 1. A game structure comprising a table with surrounding marginal portions rising above the surface of the table, with the bottom of the table of an elastic nature to rebound under blows, a playing element adapted to rest on the table, a pocket at one end of the table, and a mallet for tapping the under surface of the table adjacent to the end remote from the pocket, whereby blows delivered to the under face of and transmitted through the table will cause a playing element on the table to rise therefrom

and, if the blow be properly directed, proceed to and drop into the pocket.

2. A game-board comprising a box-like structure of fibrous material having a head 35 board, a tail board, elongated sides, and a bottom of elastic characteristics, a pocket carried by the head board on the face thereof toward the tailboard, a playing element, and a tapping implement, the bottom having 40 indicia displayed on its upper surface in distant relation to the pocket, for locating the playing elements.

3. A game-board comprising a box-like structure of fibrous material having a head 45 portion, a tail portion, elongated sides, a bottom of elastic characteristics, playing elements in the form of cubes, and a pocket carried by the head portion on the face thereof toward the tail portion, the bottom 50 having indicia displayed on its upper surface in distant relation to the pocket for locating the playing elements, and a mallet for imparting impulses to the playing elements through the bottom of the game-board, 55 the visible surface of the bottom being provided with penalty spaces for adding difficulty to the playing of the game.

In testimony that I claim the foregoing as my own, I have hereto affixed my signature.

JOSEPH CARTER.
